WITNESS:

Edwin G. McKee

INVENTOR.

F. D. Goodlake

BY

Victor J. Evans ATTORNEY.

UNITED STATES PATENT OFFICE.

FREDERICK DEENE GOODLAKE, OF MEMPHIS, TENNESSEE.

MANIFOLD-HEATER.

1,346,745.

Specification of Letters Patent. Patented July 13, 1920.

Application filed December 22, 1919. Serial No. 346,438.

To all whom it may concern:

Be it known that I, FREDERICK D. GOODLAKE, a citizen of the United States, residing at Memphis, in the county of Shelby and 5 State of Tennessee, have invented new and useful Improvements in Manifold-Heaters, of which the following is a specification.

This invention relates to means for heating the intake manifold of internal combustion engines so as to insure the vaporization of the fuel in cold weather and the principal object of the invention is to associate a chamber with the manifold which is adapted to contain a heating medium to heat 15 the manifold.

Another object of the invention is to provide a torch member with means for easily and quickly connecting it with the chamber.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the several views, and in which:—

Figure 1 is an elevation showing the invention applied to a combined exhaust and inlet manifold.

Fig. 2 is a sectional view showing the interior of the heating chamber.

Fig. 3 is a sectional view taken approximately through the center of Fig. 1.

Fig. 4 is a view, with parts broken away, showing the invention attached to the ordinary type of inlet manifold.

Referring to Figs. 1, 2 and 3, 1 indicates the exhaust manifold and 2 indicates the inlet manifold, these parts being formed integral with each other, as shown. In carrying out my invention I form a chamber 3 on the front part of the combined manifolds. The side walls of said chamber being bent inwardly to form recesses 4 to permit the cross arms, which hold the device to the engine, to engage the central part of the device. The wall of the chamber is also provided with the horizontally arranged semi-circular part 5 which extends outwardly and at one end a screw threaded opening 6 is 55 formed to receive the screw threaded head 7 of the torch member 8. This member may

be made of perforated tubing to receive absorbent material which is adapted to receive a supply of gasoline or other inflammable fluid. The front wall of the chamber is provided with an opening 9 which is covered by a hinged flap 10. This opening may be used for igniting the torch member by a match and also acts as an inlet for the air circulating through the chamber. The upper part of the chamber is provided with air openings 11. As will be seen the torch member will fit in the semi-circular chamber formed by the projection 5 and these parts are so arranged that the torch will be located adjacent the horizontal part of the inlet manifold. The rear part of the chamber extends over the upper part of the vertical portion of the manifold.

It will thus be seen that when the automobile is to be started in cold weather the torch is dipped in gasoline or the like and either ignited before being placed in the heating chamber or after it is placed in said chamber. The flame from the burning fuel 80 will quickly heat the chamber and this heat will be transmitted to the manifold and thus the explosive charge passing to the cylinders will be heated and the fuel therein vaporized.

In the modification shown in Fig. 4 the chamber 3' is formed on the inlet manifold which is separated from the exhaust manifold. In other respects this form of the invention is similar to that above described 90 and operates in the same manner.

The manifolds with my invention applied thereto may be manufactured to sell as a separate article of commerce and may be applied to existing models of automobiles 85 by the owners without any special tools as the device is simply substituted for the manifold which is originally on the car.

The arrangement of air openings in the walls of the chamber will provide sufficient 100 air for the thorough combustion of the gases arising from the torch member and will cause a circulation of air in said chamber, to produce an intense heat in the upper part thereof so that the manifold will be intensely heated very quickly to insure the proper vaporization of the fuel in the explosive mixture.

It is thought from the foregoing description that the advantages and novel features 110 of my invention will be readily apparent.

I desire it to be understood that I may

make changes in the construction and in the combination and arrangement of the several parts, provided that such changes fall within the scope of the appended claim.

5. What I claim is:—

A manifold for internal combustion engines having a heating chamber located on its outer face, said chamber having an enlarged lower part having an opening in one

end, the side walls of the chamber curving inwardly above the enlargement and having upwardly extending openings therein forming air inlets and a torch member extending into the enlarged lower part of the chamber and having screw threaded connection with 10
the opening thereof.

In testimony whereof I affix my signature.

FREDERICK DEENE GOODLAKE.
